Application December 11, 1931, Serial No. 580,289

8 Claims. (Cl. 100—39)

This invention relates to presses and more particularly to a press adapted to be used in compressing oleaginous material or seeds of certain plants to extract the oil therefrom.

5 In presses heretofore used in the extraction of oils from oleaginous material, a vertical press of the hydraulic type has been most frequently employed. This has necessitated the use of a press cloth and the intermediate step of placing 10 the material in a former, putting the material under an initial pressure to form a cake and wrapping the press cloth around it, before transferring the cake to the press where the oil is extracted. The use of the press cloth has been expensive and, in fact, has been an important item 15 of expense in the extraction of the oil from the material.

It is, therefore, an object of the present invention to design a press which will completely 20 eliminate the necessity for press cloths as now commonly used.

In the former process utilizing press cloth, considerable oil remains in the outer edges of the cake. To save this oil, the cake is run through a 25 trimmer where the oily edges are removed to be re-run through the press.

It is another object of the present invention, therefore, to provide a press which will extract the desired percentage of oil from oleaginous 30 material without leaving an excess of oil about the marginal edges thereof to be trimmed off at a later stage.

It is a particular object of the present invention to provide a rotary press which will continuously 35 press material to extract oil therefrom.

It is a further object of the present invention to provide a fully automatic feed and removal system for such a machine whereby the necessity for any labor whatever other than supervisory is 40 eliminated.

A structure embodying the invention is illustrated in the accompanying drawings and will be 45 hereinafter fully described, the invention residing in certain novel features which will be particularly pointed out in the appended claims.

In the drawings:

Figure 1 is an elevational view showing the side 50 of one unit of the machine and the drive shaft through which power to run the machine is obtained;

Figure 2 is an end elevational view of the machine taken on the line 2—2 of Fig. 1;

Figure 3 is a cross section of the machine taken 55 on the line 3—3 of Fig. 1, looking in the direction of the arrows;

Figure 4 is a cross section on the line 4—4 of Fig. 1, looking in the direction of the arrows;

Figure 5 is a cross section on the line 5—5 of Fig. 3, looking in the direction of the arrows, and showing the details of the feed mechanism; 5

Figure 6 is a cross section on the line 6—6 of Fig. 5, looking in the direction of the arrows;

Figure 7 is a cross section taken on the line 7—7 of Fig. 6, looking in the direction of the arrows and showing the clutch engaging mechanism; 10

Figure 8 is a cross section on the line 8—8 of Fig. 6, looking in the direction of the arrows and showing the detail of the plunger eccentric;

Figure 9 is a cross section on the line 9—9 of Fig. 8, looking in the direction of the arrows; 15

Figure 10 is a cross section on the line 10—10 of Fig. 1, looking in the direction of the arrows;

Figure 11 is a cross section on the line 11—11 of Fig. 6, looking in the direction of the arrows;

Figure 12 is a perspective view of the cam for 20 operating the feeding mechanism;

Figure 13 is a cross section on the line 13—13 of Fig. 11, looking in the direction of the arrows, showing a detail of one member going to make up the face of the punch; 25

Figure 14 is a cross section on the line 14—14 of Fig. 13, looking in the direction of the arrows;

Figure 15 is a cross section on the line 15—15 of Fig. 3, looking in the direction of the arrows, showing the cut-off knife; 30

Figure 16 is a cross section on the line 16—16 of Fig. 11, looking in the direction of the arrows and showing a detail of the ejecting cam;

Figure 17 is a horizontal cross section through the machine taken on the line 17—17 of Fig. 3, 35 looking in the direction of the arrows;

Figure 18 is a diagrammatic perspective of the clutch throw-out mechanism for operating the feed plunger, being a schematic view of the device shown in Fig. 7; and 40

Figure 19 is a perspective view of the punch, parts thereof being shown broken away to more clearly illustrate certain other parts.

Referring to the accompanying drawings in which like numerals indicate like parts through 45 out the several views, the machine may comprise a plurality of units, generally designated 25, mounted on a common base 26. Each unit comprises a pair of upright frames 27 and 28 upon which the mechanism for crushing the 50 seeds or other material is mounted.

The base 26 is made concave or dish-shaped as shown at 29 and has a plurality of horizontal supports 30 at spaced intervals thereon which carry the frames 27 and 28. The supports 30 55

have ports 31 therethrough to allow the passage of the extracted oil freely from one end of the base to the other. The frames 27 and 28 are mounted on the supports 30 and are adjustable 5 therein with respect to each other. As herein shown, the frame 28 is fixed to the base by a plurality of bolts 32 while the frame 27 is adjustable to and from the frame 28 by means of bolts 33 mounted in slots 34. The frames are held in 10 spaced adjusted position by means of a plurality of tie bolts 35 passing through the frame 28 and adjustably located in the frame 27 by means of nuts and lock nuts as is the common practice.

The frames 27 and 28 are formed of a body 15 portion 36 made of relatively light material and reinforced by a peripheral flange 37 and radiating ribs 39.

The frames 27 and 28 are formed with aligned hubs 39 and 40 respectively having centrally 20 aligned apertures therethrough which mount a shaft 41 therein. The shaft may be keyed by a key 42 in one of the hubs 39 or 40 so as to hold it against turning therein and may have an enlargement 43 at one end and a nut 44 threaded on the other end to maintain the shaft 25 in fixed axial position in the hubs 39 and 40.

A wheel or frame 45 is rotatably mounted on the shaft 41, a bushing 46 being fitted into the wheel 45 and freely rotatable on the shaft 41 to 30 minimize friction.

The wheel 45 has a plurality of trapezoidal apertures 47 therein which break the wheel up 35 into a rim 48, a central hub 49 and connecting spokes 50. The hub 49 has an aperture 51 passing therethrough in which is fitted the bushing 46 which has a running fit on the shaft 41 as has been described. A plurality of punches, generally designated 52, are mounted in the apertures 47 and are shaped to conform thereto. The 40 punches will be described in detail below.

The wheel 45 is turned by means of a worm wheel 53 which may be sweated and keyed onto the wheel 45 to prevent relative motion therebetween.

A thrust bearing 45a is mounted on the shaft 45 and abuts the hub 49 of the wheel 45 to absorb any thrust from the wheel in a direction away from the frame 28.

Power is transmitted from the source (not 50 shown) to the worm wheel 53 through a shaft 54 running along the entire length of the base from the power means past each of the units 25.

The shaft contains a jaw clutch, generally 55 designated 55, adjacent each of the units, the jaw clutch having a driving member 56 splined thereto and limited in its movement by a collar 57 fixed to the shaft. The driven member 58 of the clutch is fixed in axial position on the shaft 54 in the usual manner and has a pinion 59 formed integrally therewith.

The pinion 59 meshes with a gear 60 mounted 60 on a shaft 61 parallel to the shaft 54. The shaft 61 is supported by a pair of bearings 62 and 63 fixed to the base 26, a worm gear 64 being fixed 65 to the shaft between the bearings 62 and 63.

The worm gear 64 drives a worm wheel 65 which is mounted on a shaft 66, the thrust from the worm gear 64 being absorbed by a thrust bearing 67. The shaft 66 constitutes the main 70 power shaft of each individual unit 25.

The shaft 66 is mounted in bearings 68, 69 and 70 spaced across the width of the base 26, the bearing 68 being mounted directly on the base 26, while a frame 71 formed integrally with the 75 bottom 29 supports bearings 69 and 70.

A second worm gear 72 is mounted between the bearings 69 and 70 and drives the worm gear 53, the thrust from the worm gear 72 being absorbed by a second thrust bearing 73.

An extension 74 to the shaft 66 extends out the 5 back of the base and has a sprocket 75 fixed thereto to drive a feed mechanism hereinafter described.

The frame 28 has a circular aperture 76 therein in which is mounted a face plate 77 having 10 a plane face on the outside thereof abutting a corresponding plane face on the wheel 45, the punches 52 crushing the material between the inner face of the punch 52 and the face plate 77, while the aperture 47 in the wheel 45 prevents spreading of the material.

Oleaginous material from the cooker is carried by a conveyer 78 which may be a screw conveyer or other suitable type and is deposited in a supply hopper 79 where paddle agitators 80 constantly 20 agitate the mixture.

The supply hopper 79 is mounted on the upper portion of the frame 28 and is supported by a pair of radiating plates 81 and 82 which project out from the main plate of the frame 28 and support feet 83 turned outwardly from the lower edge of the hopper 79. The radiating plates 81 and 82 are joined together at the bottom thereof so as to form a feed hopper 84 corresponding in size and positioning to one of the openings 47 at 30 a point in the rotation of the wheel 45 about its axis.

A feed piston 85 is reciprocably mounted in the feed hopper 84 and is adapted to feed material from the feed hopper 84 into the apertures 47 35 in the wheel 45 as the apertures pass the port 86 in the face plate 77. The upper wall 87 of the feed piston 85 forms a cut-off for material from the supply hopper 79 so that when the plunger is in retracted position, the wall 87 of the 40 piston 85 uncovers a portion of the supply hopper 79 and allows the material to fall down into the feed hopper 84 to be compressed into the opening 47 by the piston 85.

The cams 106, as best shown in Figs. 7 and 18, 45 operate an axially moving follower 109 which has an arm 110 fixed thereto by welding or other permanent connection. The arm 110 serves to retain one end of a spring 111 for holding the follower 109 in retracted position at all times 50 when it is not being acted on by the cams 106. A pin 112 is fixed to the arm 110 and actuates a second arm 113 which is fixed to a shaft 114.

A Y 115 having inturned pins 116 at the outer ends thereof is fixed to the shaft 114 and operated 65 through the arm 113 whereby when the cams 106 operate on the follower 109, the Y 115 throws in the jaw clutch 94 as best seen in Figs. 2 and 6.

The piston 85 is driven from the sprocket 75 60 on the extension 74 of the shaft 66 through a chain 88 trained thereover which operates a sprocket 89 fixed on a tubular shaft 90. The shaft 90 is journaled in a bearing 91, the bearing being mounted to the frame 28 through a bracket 65 92. The inner end of the sleeve 90 is formed integrally with a driving member 93 of a jaw clutch 94 so as to supply power from the source through the chain 88 to the clutch.

A driven member 95 of the clutch 94 is keyed 70 on a shaft 96 which extends through the tubular shaft 90, the shaft 90 forming a bearing for one end of the shaft 96 while the opposite end of the shaft 96 is journaled in a bearing 97. The bear- 75

ing 97 is supported by a bracket 98 mounted on the frame 28.

An eccentric 99 is fixed on the shaft 96 and contains an adjustable crank pin 100 connecting the eccentric 99 with a piston rod 101, the piston rod being pivotally connected with the piston 85 by a pin 102.

The piston rod 101 is threaded at the opposite ends with threads of opposite pitch the threaded ends screwing into corresponding threads in a connecting member 102a surrounding the pin and a cross head 100a connected to the crank pin 100 so that the length of the connecting rod 101 may be varied simultaneously with the adjustment of the crank pin 100 to give various thicknesses of cake while preventing the face of the piston 85 from projecting past the outer face of the plate 77.

A plurality of springs 103 bear against the piston 85 constantly urging it into a position closing the hopper 79. The springs 103 surround guide rods 104 attached to the piston 85 and passing through ports in lugs 105 bolted to the feed hopper 84.

25 A sprocket 117 may also be attached to the sleeve 90 to operate the agitators 80 through a chain 118 and a sprocket 119.

The timing of the piston is accomplished through a plurality of cams 106 spaced about the periphery of the wheel 45 and which are preferably mounted in a circumferential dovetailed groove 107 and held in fixed position by a set screw 108.

The punches which have been generally designated 52 are best shown in the perspective view of Fig. 19, and comprise a trapezoidal section having a major base 120 and a minor base 121 and connecting sides 122 and 123. The outer surfaces of the sides 120 to 123 inclusive are provided with grooves 124 which conduct oil which is squeezed between the opening 47 and the punch 52 to the outer side of the wheel 45, where it drops to the concave bottom 29 of the base 26.

The width of the punch 52 perpendicular to its trapezoidal face is equal to the width of the wheel 45 in order to form guides which insure the moving of the punch inwardly parallel to itself which gives an even compression over the face of the cake. The outer end of the sides 122 and 123 of the punch 52 form a support with which webs 125, 126 and 127 are formed integrally to support a cam follower 128 on the outer side of the punch, the follower 128 being rotatable on a shaft 129, held in the webs 125 and 126. While the shaft 129 has been shown as stationary, with the follower 128 rotatable thereon, it will be understood that the shaft 129 may be either fixed or rotatable in the supports 125, 126 and 127.

As the follower rotates about the periphery of its cam 130, the outer portion travels a greater linear distance than the inner portion, due to the difference in diameter. The follower 128 is therefore made of a plurality of relatively thin disc sections 131 which permit the transmission 65 of the heavy stress through the cam follower 128 without undue friction between the cam and follower.

As seen in Figs. 16 and 19, the sides 122 and 123 of the punch are provided with inwardly projecting shoulders 132 which form seats for ribs 133 which form the outer face of the punch 52. The ribs which are best shown in Figs. 13 and 14 comprise a trapezoidal section 134 having rectangular end portions 135, the outer face 136 of 75 the rectangular end portions 135 being inclined

to conform with the slope of the sides 122 and 123 of the trapezoidal section.

The ribs 133 are placed in position in the trapezoidal section with the major base of the trapezoidal rib facing the inner side of the punch adjacent the face plate 77 and the minor base abutting the shoulder 132 in the sides 122 and 123. The height of the ribs 133 is such as to give sufficient strength to the ribs during the crushing of the material, the shoulders 132 being positioned so that the ribs are flush with the inner face of the punch 52.

The ribs 133 are held firmly in position by machine bolts 137 passing through a plate 138. The plate 138 is seated on shoulders 139 in the bases 15 120 and 121 of the trapezoidal section. A plurality of lugs 140 are formed on the outer edge of the sides 122 and 123 of the trapezoidal section and are arranged to abut an outer side 141 of the wheel 45 to stop the inward motion of the 20 punch 52 and prevent the passage of the inner side of the punch past the corresponding face of the wheel 45.

The punch 52 is actuated in the aperture 47 by means of the cam 130 fixed on the frame 27 by 25 bolts 142. The cam 130 is arranged to start the compression of the cake 143 at a point in the rotation of the wheel 45 past the feed hopper 84 and to continue the compression of the material between the outer face of the punch and the face 30 plate 77 to a point immediately preceding the feed hopper 84 at which point the crushed material is expelled through a port 144 by means of an expelling mechanism, generally designated 145.

The port 144 extends through both the frame 35 28 and the face plate 77 and corresponds in shape and axial position to one of the apertures 47 in the wheel 45 when in one position of its rotation.

A knife 146 may be fixed to the plate 77 and the frame 28 and run on the inner surface of the 40 wheel 45 so that when the cake is ejected through the opening 144 by the ejecting mechanism 145, the knife will pry under the face of the cake adjacent the punch 52 to loosen it from the punch and drop the cake on a chute mechanism 147 from whence it may be delivered to trucks and other suitable conveyances 148.

The ejecting mechanism, which has been generally designated 145, is best shown in Figs. 10, 11 and 16 and comprises a pair of cams 149 and 50 150, the cams being mounted on tubular shafts 151 and 152 respectively in apertures 153 through the cam 130 and the frame 27. Rectangular apertures 154 accommodate the movement of the cams 149 and 150 into the cam 130. 55

The interior of the shafts 151 and 152 is made hollow to accommodate a spring 155 which bears against a cross arm 156 of a frame generally designated 157. The frame 157 which supports the cross arm 156 comprises a stud 158 mounted in 60 the frame 27, the cross arm 156 connected to the stud adjacent the outer end thereof and pins 159 projecting through the arm 156 and aligned with the apertures in the stems 151 and 152. The springs 155 surround the pins 159, the pins 159 65 forming a guide for the frame 157 relative to the stems 151 and 152.

Lock nuts 160 are placed on the stems 151 and 152 to limit the inward movement thereof. It will be noted that the stud 158 is adjustable as 70 are the lock nuts 160 on the stems 151 and 152 so that the entire frame 157 is adjustable in accordance with the position of the frame 27 on the support 30 to expel any thickness of cake desired.

As seen in Figs. 2 and 6, the frame 28 has an 75

annular enlargement 161 of approximately semi-circular shape in cross section extending practically the entire distance between the feed hopper 84 and the expelling port 144. The enlargement 5 161 receives a steam pipe 162 entering at one end of the enlargement and passing through the enlargement directly behind the face plate 77 as clearly shown in Fig. 17. While the pipe has been shown unitary in the figures, it would undoubtedly be convenient to make it in several 10 pieces by the interposition of joints between the various sections.

The pipe 162 extends around the circumference of the enlargement 161, steam emerging 15 from the pipe 162 through a pipe 163 to enter a steam chest 164 through a port 165 therein. The steam chest surrounds the feed hopper 79 to heat the contents of the hopper and facilitate the extraction of the oil from the material. An outlet 20 166 from the steam chest 164 leads to a second unit 25 similar to the one just described.

At the proper time in the rotation of the wheel 45, the cam 106 operates a follower 109 to transmit power to the piston 85 through the shaft 66, 25 the eccentric 99 and intermediate transmission mechanism to the piston 85. At this point the eccentric 99 draws back the piston 85 allowing the material to fall into the feed hopper 84 from the supply hopper 79. By the time the feed has 30 filled the feed hopper 84 one of the openings 47 has come in register with the opening 86 in the face plate 77. The eccentric 99 together with the springs 103 then acts on the piston 85 to put an initial compression in the cake 143 and force it 35 into the opening 47. This compression is sufficient to solidify the cake but is not sufficient to begin the process of extracting oil therefrom. The movement of the cake 143 into the aperture 47 in the wheel 45 moves the punch 52 out to the 40 outermost position of the cam 130 as indicated by number 167. Upon further rotation of the wheel 45, the cam 130 slopes toward the wheel 45 and presses on the follower 128 to move the punch 52 inwardly.

45 Movement of the punch inwardly towards the face plate 77 crushes the material 143 in the aperture 47 between the punch 52 and the face plate 77. As the pressure increases on the cake 143, oil is extracted therefrom.

50 The extracted oil escapes through either the joints between the ribs 133 which form the inner face of the punch 52 or around the outside of the punch 52 between the punch and the opening 47 in which it is located or between the wheel 45 and the face plate 77.

The oil that escapes through the joints between the ribs 133 passes outwardly through the rear of the punch 52 and drops into the bottom 29 of the base 26 where it may be drawn off in any 60 convenient manner.

The oil which escapes between the punch 52 and the aperture 47 in the wheel 45 runs through the grooves 124 and drops past the open end of the punch to the bottom 29 of the base 26.

65 The oil which squeezes between the face plate 77 and the wheel 45 is collected in a pair of circumferential grooves 168 and 169 formed concentrically in the wheel 45, one on either side of the punch 52. Radial grooves 170 lead from the 70 grooves 168 to the outer periphery of the wheel. Oil squeezing radially outwardly is, therefore, collected in the groove 168, runs to a level below the shaft 41 from whence it passes out through the radial grooves 170 to the bottom 29 of the base 75 26.

The oil entering the groove 169 runs out through radial grooves 171 from whence it goes around the periphery of the shaft 41 and into a trough 172 cut in the frame 28. The trough takes the collected oil and permits it to drop into the bottom 5 29 of the base 26.

As the cake passes around the periphery of the face plate 77, the cam 130 acts to shove the punch 52 further into the aperture 47 increasing the compression in the cake as the punch advances. 10

Just as the cake approaches the opening 144 in the face plate 77, the maximum degree of compression has been reached and is relieved before entry of the cake over the area of the opening. When the cake is in full register with opening 144, 15 15 the cam follower 128 presses the cams 149 and 150 outwardly against the action of the springs 155 to force the punch 52 inwardly and expel the formed cake 143 out through the aperture.

The knife 146 then pries under the edge of the 20 cake adjacent the punch 52 and dislodges the cake from the face of the punch. If desired, the knife may be entirely eliminated by having the cake abut against a flat surface so that the cake is dislodged by the further movement of the wheel 25 45.

It will be noted that oil squeezed out of the material in the upper portion of the rotation of the wheel falls on the top of the shaft 41 and will work its way between the bushing 46 and 30 the shaft 41 to form a lubricant.

The material is heated by the steam jacket 164 while it is in the hopper and is constantly heated by the pipe 162 in the annular enlargement 161 of the frame 28 during the rotation of the wheel 45 35 about the face plate 77. This renders the oil less viscous and facilitates the flow thereof and assures proper lubrication of the shaft between the bearing 46 and the shaft 41.

The setting of the frame 27 may be varied 40 axially with respect to the frame 28 in an obvious manner hereinbefore explained, the setting of the frame 27 serving to vary the amount which the cake 143 is compressed and thereby determining the amount of oil left in the cake. 45

It will thus be seen that there has been provided a relatively simple punch which operates continuously and automatically to press oil from oleaginous material or the like and that the press is adjustable to extract any desired percentage 50 of oil from the cake.

It will also be noted that the cake is constantly heated during the pressing operation whereby the oil is more readily extracted.

While there has been shown a preferred form 55 of the invention, it is realized that the device is susceptible to various changes and modifications coming well within the scope of one skilled in the art, and it is not, therefore, desired to limit the invention to the precise form herein shown and described, but only by the scope of 60 the appended claims.

What is claimed as new and desired to secure by Letters Patent is:

1. In a press of the character described, a 65 first fixed frame having a flat face, a second fixed frame mounted in spaced parallel relation to said first frame, a shaft connecting the frames, a movable member mounted to turn about the axis of said shaft and disposed between said 70 frames with one face in flat engagement with the flat face of the first frame, said movable member having a plurality of circumferentially spaced transverse openings closed at one side by the flat face of the first frame, a punch mov- 75

ably disposed in each of said openings to press material received therein against the flat face of the first frame, an annular cam carried by the second frame, a cam follower carried by each 5 punch to ride on said cam as the movable member turns about the axis of the shaft, said cam being formed to force the punches toward the flat face of the first frame as the movable member turns, said first frame having an outlet opening 10 with which the openings successively align and through which the compressed material is ejected from the openings, and ejecting means comprising a spring pressed plunger mounted in the annular cam to be engaged by the cam followers as they ride thereover, said plunger being depressed against the action of its spring by the followers and being released to push the punches toward the first frame to expel the material from the openings as the openings align with the outlet opening in the first frame.

2. In a press for extracting oil from oleaginous material comprising, a horizontal base, provided with an oil collecting trough, a pair of upright parallel spaced frames rigidly mounted on said base, a horizontal shaft connecting the frames, a rotatable member mounted on the shaft to turn about its axis, one of said frames having a flat inner wall with which the adjacent flat face of the rotatable member engages, said 25 rotatable member having a plurality of circumferentially spaced transverse apertures closed at one side by the flat face of said frame, said frame having spaced openings with which the apertures in the rotatable member align as said member turns, one of said openings affording means for 30 depositing material into said apertures and the other providing means for the ejection of material from said apertures, a punch in each aperture to close the other side thereof and movable to compress and crush material deposited in its 35 aperture between it and the flat face of said frame, an annular cam track carried by the other frame, cam followers on the punches engaging said cam track, said cam being shaped to force the punches toward the first mentioned frame, and means carried by said cam track and 40 operable directly on the cam followers of the punches upon alignment of their respective apertures with the opening in the first frame through which ejection of compressed material 45 is effected to force the plunger toward the first frame and effect such ejection of the compressed material.

3. In a press to extract oil from oleaginous material, two spaced members fixed with respect to each other, one of said members having a plane inner surface, an annular continuous cam carried by the other member and facing said plane surface, a rotatable element disposed 55 between the cam and said plane surface, said rotatable element having a plurality of circumferentially spaced apertures closed at one end by said plane surface, punches in said apertures to press material disposed therein against said plane surface to extract oil from said material, cam followers carried by the punches and tracking on said cam to force the punches toward the plane surface as the rotatable element turns, said cam having a gradual slope from a low spot 60 to a high portion, means to successively load the apertures as they reach the low spot of the cam, and means to forcibly eject the material from said apertures after it has been compressed as the apertures reach the high portion of the cam, 65 said ejecting means including pusher members 70

projecting through the cam and movable on a line parallel to the axis of rotation of the rotatable element to engage the cam followers and urge the punches toward the plane surface to push the material through a hole in said plane 75 surface.

4. In a press to extract oil from oleaginous material, a fixed member having a plane surface, a rotatable member having a plane surface in contact with the plane surface of the fixed member and provided with a plurality of apertures closed at one end by the plane surface of said fixed member, punches in said apertures to press material disposed therein against the plane surface of the fixed member and extract 10 oil from said material, an annular stationary cam at the side of the rotatable member opposite the contacting plane surfaces, said cam having a gradual slope from a low spot to a high portion and an abrupt drop from its high portion to its low spot, cam followers carried by the punches to track at all times on said cam and actuate the punches as the rotatable member turns, means adjacent the low spot of the cam with which the apertures align as the rotatable 15 member turns for forcibly projecting and initially compressing a definite amount of material into the apertures, as they are aligned therewith, and means adjacent the high portion of the cam near its abrupt drop for ejecting the pressed 20 material from the apertures as they align therewith, said ejecting means moving on a line parallel to the axis of rotation of the rotatable member and being projectable from the high portion of the cam.

5. In a press to extract oil from oleaginous material, a fixed member having a plane surface, a rotatable member having a plane surface in contact with the plane surface of the fixed member and provided with a plurality of apertures 25 closed at one side by the plane surface of said fixed member, punches in said apertures to press material disposed therein against the plane surface of the fixed member to extract oil from said material, means with which said apertures align as the rotatable member turns for forcibly projecting and initially compressing a definite amount of material successively into the apertures as they are aligned therewith, said means comprising a movable plunger, drive means to intermittently actuate the plunger, and means on the rotatable member to control the functioning of the said drive means.

6. In a press to extract oil from oleaginous material, a fixed member having a plane surface, a 30 rotatable member having a plane surface in contact with the plane surface of the fixed member and provided with a plurality of apertures closed at one side by the plane surface of said fixed member, punches in said apertures to press material disposed therein against the plane surface of the fixed member to extract oil from said material, means with which said apertures align as the rotatable member turns for forcibly projecting and initially compressing a definite 35 amount of material successively into the apertures as they are aligned therewith, said means comprising a movable plunger, drive means to actuate the plunger, a clutch to connect the drive means with a source of power, and means to actuate the clutch and effect the functioning of the drive means for the plunger including a cam carried by the rotatable member and a cam follower operable by said cam.

7. In a press of the character described, two 40

spaced rigidly connected members, one of which has a plane inner surface, a ring mounted on the inner face of the other member, the side of the ring facing the plane surface providing a cam having a gradual slope from a low spot to a high portion and an abrupt drop from its high portion to its low spot, a rotatable element disposed between the two spaced members with one face thereof flat against the plane surface of the first mentioned spaced member, said rotatable element having a plurality of apertures to receive material to be compressed, punches in said apertures to compress material received therein, cam followers carried by the punches to ride on the cam track and actuate the punches, and means projectable on a line parallel to the axis of rotation of the rotatable element from the high portion of the cam and engageable with the cam followers as they move into alignment therewith to impart sudden outward movement to the punches and thereby eject the material from the apertures through a hole in the first spaced member.

8. In a press of the character described, a pair of parallel spaced rigid frames, a shaft connecting the frames, a member mounted to turn about the axis of the shaft and disposed between said frames, one face of said member being in flat engagement with one of the frames and said mem-

ber having a plurality of circumferentially spaced transverse apertures closed at one side by the flat face of said frame, a punch slidably disposed in each of said transverse apertures to be movable toward said frame to compress and crush material between it and the flat face of said frame, a continuous annular cam track carried by the other fixed frame directly adjacent the rotatable member, and a cam follower carried by each of said punches to ride on said cam, said cam track having a gradual slope from a low spot to a high portion to gradually force the punches into their respective apertures and having an abrupt drop from its high portion to its low spot, means adjacent the low spot of the cam track to load the apertures with material and push the punches outwardly to engage their cam followers with the low spot of the cam, and means movable on a line parallel to the axis of rotation of the rotatable member and projectable from the high portion of the cam track to engage the cam followers and impart sudden movement to the punches towards the first designated frame to eject the compressed material from the apertures through an opening in said first designated frame as the cam followers move into alignment with said means.

EUGENE V. BREITENBACH.
